GAME APPARATUS

Virgil H. Fontaine, Jr., Lubbock, Tex.

Application August 16, 1943, Serial No. 498,798

1 Claim. (Cl. 273—123)

This invention relates to a game apparatus and has for the primary object, the provision of a device of this character on which a very interesting game may be played, the game being to shoot a selected number of game pieces, each of spherical shape into zones or openings by a cue ball or spherical-shaped game piece propelled by a cue stick in the hands of a player.

Another object of this invention is the provision of an apparatus of the character set forth, which includes a rotatable playing field having a selected number of openings in which the game pieces are to be played into, said field being rotatable permits any one of the players to bring a selected portion thereof into a position for making a selected play without the player moving from a seated position or from a position of play.

A further object of this invention is, the provision of a base for rotatably supporting the playing field and provided with portions in which game pieces that have been played through the openings of the playing field may collect and be easily reached by the players.

With these and other objects in view as will become more apparent as the description proceeds, the invention consists of certain novel features of construction, combination and arrangement of parts as will be hereinafter more fully described and claimed.

For a complete understanding of my invention, reference is to be had to the following description and accompanying drawings, in which

Figure 1 is a top plan view illustrating a game apparatus constructed in accordance with my invention.

Figure 2 is a sectional view taken on the line 2—2 of Figure 1.

Figure 3 is a top plan view partly broken away showing the base with the playing field removed.

Figure 4 is a sectional view taken on the line 4—4 of Figure 3.

Referring in detail to the drawings, the numeral 5 indicates a base and 6 a cover removable therefrom for the purpose of exposing a playing field 7.

The base 5 is of rectangular shape and includes a bottom wall 8 and marginal upstanding walls 9. The base 5 further includes an annular wall 10 mounted on the bottom wall 8 inwardly of the marginal walls 9 and of a height greater than the height of the marginal walls 9. The annular wall 10 is secured on the bottom wall 8 in any suitable manner and arranged on and secured to the bottom wall 8 and centrally thereof is a bearing block 11 carrying a vertically ar-

ranged pintle 12 rotatably received within a bearing block 13 secured to the playing field 7. Thus it will be seen that the playing field is mounted on the base for rotary movement, being supported both by the bearing blocks 11 and 13 and by the annular wall 10. The playing field protrudes a limited distance beyond the annular wall so as to overhang the space occurring between the annular wall 10 and the marginal walls 9 of the base. The pintle 12 prevents the bearing blocks from moving off of each other still permitting the playing field to rotate freely.

The playing field 7 includes a disk 14 equipped with a suitable covering 15 to form the playing surface. The disk 14 has the bearing block 13 secured centrally thereof and is of octagon shape and provided with a rail 16 matching the shape of the periphery of the disk 14. The rail 16 is rabbeted to receive the periphery of the disk 14, the latter being secured into the rabbeted portion in any suitable manner. Bumper strips 17 are secured to the inner faces of the rail 16. At the corners of the rail and formed in the disk 14 are openings 18 through which game pieces of spherical shape may freely pass. The openings are designated by characters as clearly shown in Figure 1.

Arranged within the spaces between the annular wall 10 and the peripheral walls 9 are supporting blocks 18' the top faces of which are inclined in opposite directions for the purpose of supporting inclination panels 19 shaped to fit the curvature of the annular wall 10 and the marginal walls 9 with the corners thereof located lowermost so that any game pieces passing through the openings disposed thereover will collect within the corners of the spaces easily accessible to the players for replacement on the playing field. The supporting blocks 18' are located midway between the corners of the base within the spaces occurring between the walls 9 and 10 of said base so that the ends of the panels 19 will be efficiently supported with the corners of said panels located lowermost. It is preferable that the slope of the panels will be less than a 90° angle to permit said panels to fit snugly against the marginal walls 9. This arrangement will assure gravitation of the game pieces to the corners of the base as soon as they pass through 50 openings in the playing field.

As heretofore explained, the game pieces are of spherical shape and consist of groups of field pieces wherein the groups of field pieces are distinguishable by being of different colors. Further a cue game piece is employed and a cue stick

or sticks of conventional construction. It is preferable that the players take positions at the sides of the base and may occupy seated positions and with the playing field rotatably supported it may be readily turned by any one of the players to bring a selected portion of the field opposite to said player. The field pieces in the initial start of the game are grouped centrally of the playing field and the player first to shoot strikes the grouped field pieces by the cue ball propelled by a cue stick, scattering the field pieces over the playing surface. The next player then endeavors to knock one of the field pieces of his suit into an opening by striking the field piece by the cue ball propelled by the cue stick. This is continued by all of the players taking turns and should any one of the playing field pieces be knocked into an opening belonging to another player, the player making the play is penalized by having to award that field piece to the score of the opponent.

While the game has been briefly outlined in the foregoing other games may be played on this apparatus.

While I have shown and described the preferred embodiment of my invention, it will be understood that minor changes in construction, combination and arrangement of parts may be made without

departing from the spirit and scope of the invention as claimed.

Having thus described my invention, what I claim is:

5 In a game apparatus, a rectangular shaped supporting base including a bottom wall and upstanding marginal walls and an annular wall spaced from the marginal walls and of a greater height than the marginal walls, contacting bearing blocks and one of said bearing blocks secured centrally to the bottom wall, a dowel pin rotatably connecting the bearing blocks, an octagon-shaped playing field secured to one of the bearing blocks and rotatably supported thereby and by the annular wall and including a plurality of game piece openings arranged in corners thereof and outwardly of the annular wall, supporting blocks arranged between the upstanding walls and the annular wall and each having upper inclined supporting faces, and panels shaped to match the annular wall and the marginal walls and secured on the inclined faces of the supporting blocks arranging corners thereof lowermost and within the corners of the base for the collection of game pieces gravitating over the panels from the openings of the playing field.

VIRGIL H. FONTAINE, JR.
